SANDAL OR SIMILAR ARTICLE

John L. Olson, Los Angeles, Calif.

Application April 19, 1949, Serial No. 2,129

Term of patent 7 years

(Cl. D7—7)

To all whom it may concern:

Be it known that I, John L. Olson, a citizen of the United States, residing at Los Angeles, in the county of Los Angeles, State of California, have invented a new, original, and ornamental Design for a Sandal or Similar Article, of which the following is a specification, reference being had to the accompanying drawings, forming a part thereof, in which:

Fig. 1 is a rear perspective view of a sandal or similar article showing my new design, the essential features of which reside in the parts shown in full lines; and

Fig. 2 is a developed plan view of the heel only. The dominant features of my design reside in the configuration of the heel portion, seen most clearly in Fig. 2.

I claim:

The ornamental design for a sandal or similar article, substantially as shown and described.

JOHN L. OLSON.
